MOTOR AND CONTROL DEVICE THEREFOR

Wade H. Wineman, Michigan City, Ind., assignor
to Sullivan Machinery Company, a corporation
of Massachusetts

Application January 27, 1937, Serial No. 122,625

20 Claims. (Cl. 121—142)

My invention relates to motors, and more particularly to motors especially adapted to be used with pumping equipment, and provided with protective devices for automatically shutting the 5 same down in the event of a serious derangement, such as a loss of load.

A very common method of pumping oil wells involves the employment of single-acting pumping motors whose pistons, through pump rod lines, raise the plungers of pumps in oil wells, there being commonly a number of pumping motors and wells arranged around or adjacent a source of operating fluid for the pumping motors; and desirably there is provided means for pre- 10 heating the operating medium before its use in the pumping motors, and for returning it, after it has worked in the pumping motors, to the pressure creating means, when such means is of the well known type including a compressor and 15 actuating means for the latter. Such systems do not ordinarily have attendants at individual wells, and accordingly the pumping installations may become deranged and remain deranged for some little time before they receive attention. 20 For example, sometimes the highly stressed pump rods break, and in this event the motor piston might, relieved of its load, move upward with such rapidity as to cause serious damage either to the pumping motor itself or to the pump rod line which remained attached to the motor 25 piston. Moreover, damage might result from the continued operation of the pump motor without its normal load. Devices for avoiding these results form the subject matter of other applications which I have filed, and in this present application I disclose an arrangement in which a 30 valve is provided, which may close, desirably under the forces produced by the flowing motive fluid, to shut off all motive fluid supply to the pumping motor in the event that a pump rod breaks; and I have provided means which will 35 prevent undesired closing of the valve during momentary periods of fluid flow at a rate in excess of normal, so that the valve shall not close 40 during the period immediately following the commencement of admission to the pumping motor, when the fluid is flowing into the latter at a high rate—due to the fact that its entrance is opposed only by exhaust pressure, and also because the piston is free to move at a lesser pressure—or at a higher rate—during the time the 45 pump rod line is stretching.

An object of my invention is to provide an improved pumping or other motor. Another object of my invention is to provide an im-

proved safety device for shutting down an expandible chamber motor in the event said motor loses its load. A further object of my invention is to provide an improved safety device for a reciprocating motor responsive to the motive fluid supply to said motor and rendered inoperative during certain periods in the cycle of said motor, but rendered operable at other times in said cycle when the existnce of abnormal conditions would render its operativeness imperative. Still 5 another object of my invention is to provide an improved motor having improved means associated therewith for cutting off the fluid supply thereto, said means held inoperative during the early portions of the working stroke of said 10 motor, but thereafter rendered operative under the control of the moving motor element. Other objects and advantages of my invention will appear in the course of the following description.

In the accompanying drawings, in which for 20 purposes of illustration one embodiment which my invention may assume in practice has been shown,

Fig. 1 is a view in side elevation showing a 25 pumping motor equipped with a controlling device in accordance with the illustrative embodiment of the invention.

Fig. 2 is a section through the distributing valve and the lower end of the cylinder of the 30 motor shown in Fig. 1.

Fig. 3 is a view on an enlarged scale and with 35 some parts shown in section, on the plane of the line 3—3 of Fig. 2, through a portion of the distributing valve mechanism, with parts in a different position from Fig. 2.

Figs. 4, 5 and 6 are similar views, partially in 40 section, showing the positions of the automatic control valve respectively shortly after admission commences, after admission has been in process long enough to take up at least most of the slack in the pump rods and to build up the cylinder pressure, and after the automatic controlling valve has been rendered operative and has closed off the supply of working fluid to the motor cylinder.

Referring to the drawings, it will be noted that 45 a motor 1 comprises a cylinder element 2 having a bore 3 and an upper head 4 and a lower head 5, the cylinder element and the two heads being held together by side rods 6. Within the bore 50 3 is reciprocable a piston 7 whose piston rod 8 is adapted to be connected to a rod line leading to a pump in a well, in alinement with which the pumping motor 1 is supported through a connecting device, of which a fragment is shown at 55

9. The motor is adapted to be supplied with operating fluid through a connection 11, and the operating fluid passes through an automatic controlling valve mechanism 12, later more fully described, and then into a chamber 13 in the lower motor head 5. A suitable exhaust is provided for the motor communicating with a chamber 14 which is formed in the lower head 5 below the supply space 13. A port 15, communicating with 10 an annular chamber 16 between the chamber 13 and the chamber 14, opens through the lower head of the motor into the cylinder bore 3. Within a stepped bore 18 in the head member 5 there is arranged a valve-chamber-forming sleeve 15 19 provided with ports 20 communicating with the supply space 13, 21 communicating with the port 15, and 22 communicating with the exhaust space 14. The sleeve 19 is provided with bores 23 and 24, the bore 23 being the larger and the 20 upper of the two. The lower end of the bore 24 is closed by a head 25, and a passage 26 formed in said head and a clearance 27 around the lower end of the sleeve 19 provide constant communication between the exhaust space 14 and the 25 lower end of the bore 24. Within the bores 23 and 24 is reciprocable a plural-spool valve 30 comprising a lower cylindrical portion 31 fitting the bore 24 and spaced by an annular groove 32 from an intermediate cylindrical portion 33. 30 Another annular groove 34 intervenes between the head or cylindrical portion 33 and the upper, larger end 35 of the valve. The parts 31, 33 and 35 are suitably ringed or otherwise formed to prevent leakage. The groove 32 in the position 35 of the valve shown in Fig. 2 connects the lower end of the cylinder to exhaust through port 15, openings 21, groove 32, openings 22 and space 14. When the valve is in the position shown in Fig. 3, fluid is supplied from supply space 13, through 40 the groove 32, to the port 15, to effect the working stroke of the piston. The structure of the valve mechanism is well illustrated in other applications of mine and needs not be very extensively described, as this particular valve mechanism is 45 but one of many which might be used to accomplish the desired purpose. To make this application wholly clear without reference to other disclosures, it may be said, however, that the valve element 30 carries a resiliently protruded 50 check valve element 37 yieldingly held, as by a spring 38, in protruded position and adapted to seat yieldingly, as shown in Fig. 3, in a stationary valve seat 39 arranged in the top head member 40 of the valve chest. A passage 41, surrounded 55 at its lower end by the seat 39, leads by way of a connection 41' to a point of communication 42 comparatively low in the cylinder member 2, the point of communication 42 being arranged in a position to be uncovered by the upper end of 60 the downwardly moving piston 7 at such a time as to permit the provision of an adequate cushion pressure. There is also provided in the head 40 another ported valve element 44, whose stem 45 is adapted to be engaged by the upwardly moved 65 valve element 30, when the latter is in the position shown in Fig. 3, so that the valve is forced off of its seat 46. It will be noted that the valve 44 has port means 47 through it in such position that when the valve is unseated, the top end of the bore 23 communicates freely with a passage 49 which leads, by means of a connection 50, to a point of communication 51 with the cylinder bore 3, the point 51 being so arranged with respect to the cylinder that the same is uncovered 70 by the lower end of the upwardly moving piston 75

7 as the latter attains substantially the desired uppermost position thereof.

The upper end of the cylinder bore 3 is connected normally with the atmosphere through a suitable automatic relief valve device 52, described in my copending application Serial No. 102,987 and operative to permit breathing of the cylinder without substantial rises in pressure above atmospheric, or drops in pressure below atmospheric. This apparatus acts automatically to cause the building up of a back pressure above the motor piston in the event that excessive rates of speed of the latter are developed, as explained in said application, Ser. No. 102,987. During normal motor operation, as above noted, it maintains the space above the piston 7 at very close to atmospheric pressure.

The mode of operation of this portion of the mechanism will be readily understood from what has been said. When the distributing valve 30 is in the position shown in Fig. 2, the downwardly moving piston 7 will not have quite attained to a position where the upper end thereof will have passed below the point of communication 42. When the downwardly moving piston does have its upper end move below the point 42, the pressure which has been acting within the bore 23 to maintain the valve 30 in its position of Fig. 2, will be vented to atmosphere through the passage 41, and the valve 30 will move, under the action of the back pressure in the exhaust line, up to the position shown in Fig. 3 and will unseat the valve 44, while the valve element 37 will seat upon the seat 39. In this reversed position of the distributing valve, motive fluid will pass from the chamber 13, through the port 15, and begin to cause upward movement of the motor piston 7. The flow from the chamber 13 at this time will be rather rapid, compared with that during the mid-portions of the piston stroke, because the back pressure which prevailed in the motor cylinder prior to the reversal of position of the valve is materially less than the normal working pressure within the cylinder, and because, moreover, the rod line tends to stretch initially and the piston is therefore able to move with less than its full load until the stretch is out of the rod line.

The piston will continue to move upwardly as motive fluid is admitted beneath the same. As soon as its lower end passes above the connection point 42, fluid from the working cylinder would enter the chamber 23 and force the valve 30 down, were it not for the fact that the valve 37 is held seated sufficiently positively to prevent flow through the passage 41. When the lower end of the piston 7 gets above the connection point 51, motive fluid will pass through the passage 49, through the passage 47, and through the valve seat 46, and enter the space above the valve 30 and start the latter downwardly. As soon as the valve 30 moves a short distance downwardly, the valve 37 will be opened, and the further downward movement of the distributing valve 30 will be effected by pressure flowing through the connection 41. Obviously, as soon as the distributing valve has moved downwardly a short distance, the valve 44 will seat, and it will remain seated until it is again forced open by the next upward movement of the distributing valve. The lower end of the motor cylinder will be connected to exhaust, in the position of the valve 30 which it will assume as a result of the events just described. Then the motor piston will begin to move down and its upper end will first pass below

the connection point 51. Because valve 44 is seated, this will not vent the space 33 above the distributing valve. Only when the motor piston gets down below the connection point 42 will the pressure which has been holding the valve 30 in its lower position vent again, and the valve itself be again moved to admission position by exhaust line pressure on its lower end.

Now, it will be noted that it has been pointed out that the motor piston will move upwardly comparatively rapidly for a short distance during the early portion of its stroke, and will then move with a relatively constant, slower rate until the time of cut off. Should the rod line break, or a pump packing blow out, the motor piston would move upward considerably more rapidly, and would accelerate very rapidly, as a result allowing the fluid to flow into the motor cylinder at a much faster rate. This fact is taken advantage of in the structure 12 which I shall now describe.

It will be observed that the valve mechanism 12 provides an inlet chamber 60 with which the supply connection 11 communicates and a discharge chamber 61 which is in communication with the supply space 13. A septum 62 separates the spaces 60 and 61 and is traversed by a passage 63 surrounded by a valve seat 64 with which a poppet-type valve 65 is adapted to cooperate.

Normally, the valve 65 stands in the position shown in Figs. 4 and 5, being supported in the desired unseated position by the post 66. Clearly, in such a position the valve is subject to the rush of fluid through the port or passage 63, and if the velocity of the fluid is sufficiently high the valve 65 will be moved upward and will close the passage 63, unless prevented by some appropriate means. I have provided means for preventing closure of the valve 65 during the periods when the flow rate through the passage 63 is fairly high during the early portions of normal motor-piston up-strokes, this means being rendered inoperative to hold the valve open as soon as the motor piston has gotten up to a position where it travels at what might be called its normal rate during the major portions of the working stroke of the pumping motor. It will be noted that in alignment with the passage 63 there is a casing formed upon the valve chamber, this casing 67 having a chamber 68 therein into which the stem 69 of the valve 65 projects. A cover 70 is adjustably mounted on the top of the casing 67. Suitably associated with the casing—herein formed in a detachable cylinder member 71 secured to the casing—is a cylinder bore 72 in which a lock-controlling plunger 73 is reciprocable, said plunger normally pressed by a spring 74 toward the unlocking position shown in Fig. 6 of the drawings. The plunger is traversed by an opening 75 through which the valve stem 69 extends, and carries a pin 76 which is adapted to engage in a groove 77 in the plunger in certain positions of the latter, to wit, in the desired open position thereof. The provision of an appropriate clearance, as at 78, places the interior of the chamber 68 in communication with the space 61 so that whenever there is admission to the pumping motor there is also a similar pressure within the chamber 68. The cylinder bore 72 is connected through a suitable connection 80 with a point 81 in the cylinder bore 3, so arranged that it will be uncovered by the upwardly moving piston 7 only when the latter has, as it were, "settled down" to its normal rate of upward movement.

Now referring to Figs. 4, 5 and 6, the mode

of operation of this safety device may be readily understood. Fig. 4 shows the position of the parts during the first portion of the up-stroke of the motor piston. It will be observed that the pin 76 is seated in the notch 77 in the valve stem 69. Accordingly, although there is a flow of operating medium through the passage 63 with a sufficient velocity to close the valve 65 if the latter were free to move, said valve is locked against closing. It may be noted that the inner end of plunger 73 is subjected to a pressure the same as the admission pressure to the motor, and accordingly, since the outer end of the plunger is subjected only to substantially atmospheric pressure, because the connection point 81 is above the motor piston, the spring 74 is compressed and held so. Now referring to Fig. 5, it will be observed that the piston 7 has passed above the connection point 81. As a result, motive fluid passes around the cylinder to act on the left hand end of the plunger 73, and said plunger, being subjected to like fluid pressures upon its opposite ends, and being subjected to the pressure of the spring 74 upon its left hand end, moves over and frees the valve 65 from the holding action of the pin 76. However, the piston 7 has now slowed down and is now moving only at a rate such that the flow through the passage 63 is inadequate in velocity and volume to raise and seat the valve 65. In Fig. 6 the rod line is assumed to have broken. The piston 7 has therefore speeded up, and the fluid has rushed through the passage 63 at such a rate that the valve 65, being free to close, has been carried up to closed position by the rushing fluid; and here it will remain, seated, in view of the differential pressures and differential areas which result. It will of course be appreciated that the shutting off of further admission to the lower end of the cylinder will cause a slackening of the upward piston movement, and thereby reduce the risk of damage as a result of the breaking of the rod line.

It will be noted that I have provided an improved apparatus for controlling the operation of the pumping motor. It will be noted that this device, while responsive to the flow of motive fluid to the pumping motor, is prevented from operating during the periods when fluid velocity exceeds that of normal motor operation. It will be observed, however, that this momentary inoperability of the valve is of brief duration, and that there is abundant time to close off the fluid supply and thereby reduce the upward velocity of the motor piston, before a serious injury could result. The structure is simple, positive, reliable and inexpensive, and may readily be used with other safety devices, if desired.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In combination, a motor including a cylinder, distributing valve mechanism, a piston, and fluid supply and exhaust means for said motor, and means for automatically controlling fluid supply through said fluid supply means including a valve operative on closing to shut off fluid supply, means for subjecting said valve to a closing tendency during admission to said motor, and

means for positively holding said valve against closing movement during only the initial portions of the working strokes of said motor.

2. In combination, a motor including a cylinder, distributing valve mechanism, a piston, and fluid supply and exhaust means for said motor, and means for automatically controlling fluid supply through said fluid supply means including a valve operative on closing to shut off fluid supply, means for subjecting said valve to a closing tendency during admission to said motor, and means governed by motor cylinder pressure for positively holding said valve against closing movement during only the initial portions of the working strokes of said motor.
3. In combination, a motor including a cylinder, distributing valve mechanism, a piston, and fluid supply and exhaust means for said motor, and means for automatically controlling fluid supply through said fluid supply means including a valve operative on closing to shut off fluid supply, means for subjecting said valve to a closing tendency during admission to said motor, means for positively holding said valve against closing movement during only the initial portions of the working strokes of said motor, and means for subjecting said last mentioned means to a release-effecting pressure when the motor piston assumes its normal rate of movement.
4. In combination, a motor including a cylinder, distributing valve mechanism, a piston, and fluid supply and exhaust means for said motor, means for automatically controlling fluid supply through said fluid supply means including a valve operative on closing to shut off fluid supply, means for subjecting said valve to a closing tendency varying with the rate of admission during admission to said motor, and means for precluding closure of said valve during normal full pumping strokes of said motor.
5. In combination, a motor including a cylinder, distributing valve mechanism, a piston, and fluid supply and exhaust means for said motor, means for automatically controlling fluid supply through said fluid supply means including a valve operative on closing to shut off fluid supply, means for subjecting said valve to a closing tendency varying with the rate of admission during admission to said motor, and releasable means governed by cylinder pressure for precluding closure of said valve during a predetermined portion of the working stroke of said piston.
6. In combination, a motor including a cylinder, distributing valve mechanism, a piston, and fluid supply and exhaust means for said motor, means for automatically controlling fluid supply through said fluid supply means including a valve operative on closing to shut off fluid supply, means for subjecting said valve to a closing tendency varying with the rate of admission during admission to said motor, and means actuated into locking position by supply pressure for precluding closure of said valve during a predetermined portion of the working stroke of said piston.
7. In combination, a motor including a cylinder, distributing valve mechanism, a piston, and fluid supply and exhaust means for said motor, and means for automatically controlling fluid supply through said fluid supply means including a valve operative on closing to shut off fluid supply and biased in a closing direction during admission to said motor by forces varying with the rate of flow past it, locking means for precluding valve closure biased in a locking direction by supply pressure, and means for releasing said locking

means including means for subjecting the same to motor cylinder pressure.

8. In combination, a motor including a cylinder, distributing valve mechanism, a piston, and fluid supply and exhaust means for said motor, and means for automatically controlling fluid supply through said fluid supply means including a valve operative on closing to shut off fluid supply, means for subjecting said valve to a closing tendency during admission to said motor, and means for controlling valve movement including a locking plunger constantly biased in an unlocking direction, means operative during the period of motor operation for exerting an opposite, superior force on said locking plunger, and means controlled by motor piston movement for offsetting said last mentioned force early in each working stroke of said motor piston.

9. In combination, a motor including a cylinder, distributing valve mechanism, a piston, and fluid supply and exhaust means for said motor, and means for automatically controlling fluid supply through said fluid supply means including a valve operative on closing to shut off fluid supply, means for subjecting said valve to a closing tendency during admission to said motor, and means for controlling valve movement including a locking plunger constantly biased in an unlocking direction, means including a connection with motor fluid supply operative during the period of motor operation for exerting an opposite, superior force on said locking plunger, and means controlled by motor piston movement for offsetting said last mentioned force early in each working stroke of said motor piston.

10. In combination, a motor including a cylinder, distributing valve mechanism, a piston, and fluid supply and exhaust means for said motor, and means for automatically controlling fluid supply through said fluid supply means including a valve operative on closing to shut off fluid supply, means for subjecting said valve to a closing tendency during admission to said motor, and means for controlling valve movement including a locking plunger constantly biased in an unlocking direction, means including a connection with motor fluid supply operative during the period of motor operation for exerting an opposite, superior force on said locking plunger, and means controlled by motor piston movement for offsetting by fluid pressure said last mentioned force early in each working stroke of said motor piston.

11. In combination, a motor including a cylinder, distributing valve mechanism, a piston, and fluid supply and exhaust means for said motor, pump rods actuated by said piston, and means for automatically controlling fluid supply through said fluid supply means including a valve operative on closing to shut off fluid supply, means for subjecting said valve to a closing tendency varying with the rate of admission during admission to said motor, and means for precluding closure of said valve, said last mentioned means having controlling means including a connection with the cylinder bore at a point passed by the piston on its working stroke when the stretch is mainly out of the pump rods.

12. In combination, a motor including a cylinder, distributing valve mechanism, a piston, and fluid supply and exhaust means for said motor, pump rods actuated by said piston, and means for automatically controlling fluid supply through said fluid supply means including a valve operative on closing to shut off fluid supply, means for sub-

jecting said valve to a closing tendency varying with the rate of admission during admission to said motor, and releasable means governed by cylinder pressure for precluding closure of said valve, said last mentioned means having controlling means including a connection with the cylinder bore at a point passed by the piston on its working stroke when the stretch is mainly out of the pump rods.

13. In combination, a motor including a cylinder, distributing valve mechanism, a piston, and fluid supply and exhaust means for said motor, pump rods actuated by said piston, and means for automatically controlling fluid supply through said fluid supply means including a valve operative on closing to shut off fluid supply, means for subjecting said valve to a closing tendency varying with the rate of admission during admission to said motor, and means actuated into locking position by supply pressure for precluding closure of said valve, said last mentioned means having controlling means including a connection with the cylinder bore at a point passed by the piston on its working stroke when the stretch is mainly out of the pump rods.

14. In combination, a motor including a cylinder, distributing valve mechanism, a piston, and fluid supply and exhaust means for said motor, and means for automatically controlling fluid supply through said fluid supply means including a valve operative on closing to shut off fluid supply, means for subjecting said valve to a closing tendency, during admission to said motor, which varies with the rate of flow to said motor, means for holding said valve against closing, and means for releasing said holding means after a predetermined motor piston movement.

15. In combination, a motor including a cylinder, distributing valve mechanism, a piston, and fluid supply and exhaust means for said motor, and means for automatically controlling fluid supply through said fluid supply means including a valve operative on closing to shut off fluid supply, means for subjecting said valve to a closing tendency, during admission to said motor, which varies with the rate of flow to said motor, and means for holding said valve against closing during the initial part of the working stroke of said piston, said means having a controlling piston, and means for subjecting the latter to motor cylinder pressure after predetermined motor piston movement.

16. In combination, a motor including a cylinder, distributing valve mechanism, a piston, and fluid supply and exhaust means for said motor, and means for automatically controlling fluid supply through said fluid supply means including a valve operative on closing to shut off fluid supply, means for subjecting said valve to a closing tendency, during admission to said motor, which varies with the rate of flow to said motor, and means for holding said valve against closing during the initial part of the working stroke of said piston, said means having a controlling ele-

ment constantly subjected in a locking direction to supply pressure and in an opposite direction to a lesser yielding pressure, and means for counterbalancing said supply pressure with cylinder pressure.

17. In combination, a motor including a cylinder, distributing valve mechanism, a piston, and fluid supply and exhaust means for said motor, and means for automatically controlling fluid supply through said fluid supply means including a valve operative on closing to shut off fluid supply, means for subjecting said valve to a closing tendency, during admission to said motor, which varies with the rate of flow to said motor, and means for holding said valve against closing during the initial part of the working stroke of said piston, said means having a controlling element constantly subjected in a locking direction to supply pressure and in an opposite direction to a lesser yielding pressure, and means controlled by motor piston movement for counterbalancing said supply pressure with cylinder pressure.

18. In combination, a motor including a cylinder, distributing valve mechanism, a piston, fluid supply and exhaust means for said motor, and means for automatically controlling fluid supply through said fluid supply means including a valve operative on closing to shut off fluid supply, means for subjecting said valve to a closing tendency during admission to said motor, means for positively holding said valve against closing movement during only the initial portions of the working strokes of said motor, and means for subjecting said last mentioned means to a release-effecting pressure after the motor piston travels a predetermined distance on its working stroke.

19. In a fluid actuated motor, relatively reciprocable cylinder and piston elements, fluid supply and exhaust means, fluid distribution means for supplying motive fluid to and exhausting fluid from said cylinder element to effect relative reciprocation of said elements, and means controlled automatically by the rate of fluid flow in said supply means for automatically cutting off said supply when the rate of relative reciprocation between said cylinder and piston elements becomes excessive during a predetermined portion of the relative reciprocation of said elements.

20. In a fluid actuated motor, relatively reciprocable cylinder and piston elements, fluid supply and exhaust means, fluid distribution means for supplying motive fluid to and exhausting fluid from said cylinder element to effect relative reciprocation of said elements, means controlled automatically by the rate of fluid flow in said supply means for automatically cutting off said supply when the rate of relative reciprocation between said cylinder and piston elements becomes excessive during a predetermined portion of the relative reciprocation of said elements, and means for rendering said automatic control means ineffective during the remaining portion of relative reciprocation of said elements.

WADE H. WINEMAN.
